UNITED STATES PATENT OFFICE.

WILLIAM H. WILLIS AND JAMES H. COWEN, OF NEW BEDFORD,
MASSACHUSETTS.

HARNESS-BUCKLE.

SPECIFICATION forming part of Letters Patent No. 363,036, dated May 17, 1867.

Application filed January 19, 1887. Serial No. 221,742. (No model.)

To all whom it may concern:

Be it known that we, WILLIAM H. WILLIS and JAMES H. COWEN, citizens of the United States, residing at New Bedford, in the county 5 of Bristol and State of Massachusetts, have invented a new and useful Improvement in Harness-Buckles, of which the following is a specification.

The accompanying drawings illustrate our invention, in which—

Figure 1 is a side view of the buckle as it appears when applied to a harness. Fig. 2 is a side view of that part of the buckle which is provided with the tongue or spur and locking-spring. Fig. 3 is a view of the under side of Fig. 2. Fig. 4 is a side view of the clasp or thimble of the buckle. Fig. 5 is a view of the under side of Fig. 4. Fig. 6 is a side view of the buckle as it appears when the clasp or part 15 *a* is removed from the tongue or part *b* in order to take up or loosen the strap. Figs. 2 and 3 show the construction of the part *b* of the buckle.

c is a spur or stud, designed to enter a hole 25 in the strap *g*, and serves to resist the strain. *e* is a cross-bar, around which one end of a strap is looped and fastened, and *d* is a spring which serves to hold the two parts of the buckle *a* and *b* together when they are properly adjusted.

Figs. 4 and 5 show the construction of the clasp or thimble *a*, which is provided on its under side with a projection, *f*, designed to catch over the spring *d* of the part *b* when the parts *a* and *b* are adjusted together.

Fig. 6 represents the operation of the buckle, showing the two parts *a* and *b* of the buckle ready to be adjusted together, the part *b* hav-

ing the end of one of the straps looped around its cross-bar *e* and securely fastened. The 40 spur or stud *c* is adjusted in the desired hole in the strap *g*, which has been previously passed through the clasp or thimble *a*. Then the thimble or clasp *a* is adjusted over the part *b*, when the projection *f* of the part *a* 45 catches over the end of the spring *d*, which operation serves to hold the thimble *a* securely in place, as shown in Fig. 1.

In readjusting the buckle to a different position on the strap *g*, the spring *d* is depressed 50 by the finger and the clasp or thimble *a* moved to one side, when the spur or stud *c* can readily be adjusted in a different hole in the strap *g* and the thimble *a* replaced.

The advantages of this device over the ordinary buckle are, first, the straps are kept in a straight position, whatever the strain may be on them, and are thus not so liable to crack and break as when the ordinary buckle is used; second, it is more easily operated; and third, 60 it presents a much more neat and slight appearance.

Having thus described our invention, what we claim, and desire to secure by Letters Patent, is—

A buckle consisting of the part *b*, provided with the cross-bar *e*, stud *c*, and spring *d*, and the clasp or thimble *a*, provided with the projection *f*, substantially as shown and described.

WILLIAM H. WILLIS.
JAMES H. COWEN.
